HOOD FOR ATTACHMENT TO DIAMOND TOOLS

John L. Petrie, Detroit, Mich., assignor to Wheel Trueing Tool Company of Delaware, Detroit, Mich., a corporation of Delaware

Application December 24, 1940, Serial No. 371,469

10 Claims. (Cl. 125—11)

This invention relates to a hood attachment for diamond dressing tools.

Heat is generated at the diamond point of a dressing tool applied to the face of a rotating grinding wheel. Since it is known that this heat affects the diamond pointed tool adversely, many conventional dressing devices comprise means for emitting a jet of cooling water against the face of the wheel being dressed immediately ahead of the point of application of the tool. However, the water flowing against the face of the fast turning wheel tends to splash and also to rebound from the dressing tool in a manner that does not permit the water actually to contact and cool the diamond point. In some devices the water is prevented from reaching the diamond point by the centrifugal force of the rotating wheel which may throw the water away from the face of the wheel. The cooling devices of conventional dressing tools are therefore not satisfactory.

The hood of the present invention comprises a U-shaped shield for the diamond pointed tool. The legs of the U form leading wings that catch the streaming water or other coolant and guide the same past the diamond point. The trailing bridging portion of the shield defined by the bight of the U is slotted, to permit the grit cut from the face of the wheel to escape. Since the slot in the trailing end of the hood is much narrower than the opening between the leading ends of the legs, the water tends to fill the hood and to swirl around therein, thus cooling the diamond effectively.

Hoods according to this invention are particularly well adapted for use in conjunction with the "Diamond dressing tool" disclosed in my pending application, Serial No. 349,513, filed August 2, 1940.

It is therefore an important object of the present invention to provide means for guiding a stream of coolant into constant intimate contact with the diamond point of a dressing tool applied to the face of a rotating grinding wheel.

A more specific object of the invention is to provide a hood attached to a diamond pointed dressing tool for grinding wheels which comprises paired spaced shields disposable on each side of the diamond point whose leading ends form projecting wings and whose trailing ends are deflected toward each other into closely spaced relationship.

Other and further important objects of this invention will become apparent from the specification and appended claims.

This invention (in a preferred form) is illustrated in the drawing and hereinafter more fully described.

On the drawing:

5 Figure 1 is a fragmentary end elevational view, with parts in cross section, of a grinding wheel and a diamond pointed dressing tool with an attached hood according to this invention and a water jet, as assembled for an external dressing operation.

10 Figure 2 is a fragmentary end elevational view, with parts in cross section of a grinding wheel and a diamond pointed dressing tool with an attached hood according to this invention and a water jet as assembled for a dressing operation on a centerless grinder.

15 Figure 3 is a side elevational view with parts broken away and in section, of a dressing tool having diamonds arranged in tiers inwardly of the end thereof as disclosed in my application, Serial No. 349,513 and a hood according to the present invention attached to said tool.

20 Figure 4 is a front elevation of the assembly shown in Figure 3.

25 Figure 5 is a bottom plan view of the assembly shown in Figure 3.

30 Figure 6 is a side elevational view with parts broken away and in section, of a dressing tool similar to the tool shown in Figure 3 together with a hood according to this invention attached to the tool in a different manner.

35 Figure 7 is a side elevational view, with parts broken away and in section, of a dressing tool similar to the tool shown in Figure 3 together with a hood according to this invention attached to the tool in still another manner.

40 Figure 8 is a bottom plan view of the assembly shown in Figure 7.

45 Figure 9 is a transverse cross-sectional view along the line IX—IX through the assembly shown in Figure 7.

Similar parts in the various figures are indicated by like numerals.

As shown on the drawing:

50 In Figure 1, there is shown an assembly including a grinding wheel 10. Means, not shown, hold the wheel 10 for rotation during the grinding operation in the direction of the arrow. A tool holder 11 serves to hold a diamond pointed tool 12 in external dressing relationship to the surface of the grinding wheel 10. A pipe 13 jets water onto the surface of the grinding wheel 10 ahead of the point of application of the tool 12. The streaming water jetted onto the wheel by

the pipe 13 is guided into close contact with the point of the dressing tool by a hood 14.

In Figure 2 there is shown an assembly including a grinding wheel 10 and a mounting indicated generally by the reference numeral 15 for holding the grinding wheel 10 for rotation in the direction of the arrow during the dressing operation. A tool holder 11 serves to hold a diamond pointed tool 12 in external dressing relationship on a centerless grinder to the surface of the grinding wheel 10, the tool being retained in the holder by means of a setscrew 16. A pipe 13a jets water onto the surface of the wheel 10 ahead of the point of application of the tool 12. The streaming water jetted onto the wheel by the pipe 13a is guided into close contact with the point of the dressing tool by a hood 14.

As shown in Figures 3 to 5, the tool 12 comprises a cylindrical shank 20 from which extends an offset end 21 of reduced thickness. Tapering shoulders 22 extend laterally from the upper terminus of the end 21. The end 21 has a rectangularly flat end face or bottom 23. The metal of the tool end 21 comprises a matrix in which are embedded a plurality of diamonds 24 some of which project from the end face 23.

The hood 14 includes an upper hollow tubular portion or shank 30 seated around the lower end of the tool shank 20 and affixed thereto by spot welds 31. A lower U-shaped portion has a lower edge 32 which extends in parallelism with the tool end face 23, i. e., with its trailing bridging end portion or bight projecting further from the tubular portion 30 than its leading free leg ends, to conform roughly to the form of the wheel to be dressed. This lower U-shaped portion comprises a semi-circular segment 33 slotted axially at 34 joining projecting wings 35.

Figure 6 shows a dressing tool hood assembly similar to that shown in Figures 3 to 5 except that the hood is attached to the shank of the dressing tool by means of a terminally upset pin 40 piercing the shank 20 and the tubular hood portion 30 instead of by means of spot welding.

Figures 7 to 9 show a dressing tool hood assembly in which the tool, while generally similar to those shown in Figures 3 to 6, is characterized by a circumferential groove 41 around the lower end portion of the tool shank 20. The tool end 21a is a constricted axial prolongation beyond a circumferential shoulder 22a of the tool shank 20 and terminates in a rounded end face 23a. The hood made from spring-hardened steel is formed with indentations 42 that snap into engaging relationship with the groove 41 to attach the hood to the tool. The tubular portion 30 is split by a longitudinal slot 43 opposed to the slot 34.

The hoods described hereinabove function in the manner illustrated in Figures 1 and 2. The water jetted onto the grinding wheel turning at a speed of about one mile per minute is caught by the wings of the hood and directed around the point of the tool to cool the same. Grit cut from the face of the wheel is washed out through the slot in the hood.

The hood is brought into engagement with the wheel during the dressing operation and is worn down at the same rate as the tool end. Thus the hood soon conforms with the exact contour of the wheel being dressed.

Hoods for dressing tools according to this invention are not limited to the illustrative examples described hereinabove but include broadly

any and all means associated with pointed dressing tools for collecting coolant on the face of a grinding wheel rotated relative to the dressing tool and directing the water around the point of the dressing tool. The hood may well be V-shaped instead of U-shaped, and need not be constructed integrally but may comprise unconnected converging shields. If separate shields are used as means for coolant collecting and directing they can be secured to the tool by means other than a tubular portion seated on the tool end. For instance, pins projecting from the shields into engaging relationship with bores in the tool end can be used.

The hoods of this invention prolong the useful life of diamond pointed dressing tools far beyond what prior art workers have thought possible.

Since many details of construction may be varied within a wide range without departing from the principles of this invention, it is not my purpose to limit the patent granted on this invention otherwise than necessitated by the scope of the appended claims.

I claim:

1. A hood for a diamond pointed dressing tool including a shank and a constricted pointed end portion, said hood comprising a tubular portion adapted to be seated on said shank and a U-shaped shield portion with wing-like legs projecting ahead of the end portion of said pointed tool and a longitudinally slotted bight portion adapted to trail said pointed tool end.

2. A hood for a diamond pointed tool for dressing the face of a grinding wheel including a shank and a constricted pointed end portion, said hood comprising a tubular portion adapted to be seated on said shank and a U-shaped shield having legs forming wings adapted to project ahead of said pointed tool end portion and a longitudinally slotted bight adapted to trail said pointed tool end, the terminal edge of said shield receding from the trailing to the leading ends thereof to conform to the shape of said wheel.

3. A hooded diamond pointed tool for dressing the face of a grinding wheel comprising a shank, a constricted pointed end portion, a tubular segment seated on and welded onto said shank and a U-shaped shield integral with said tubular segment having a longitudinally slotted trailing bight and leading leg portions.

4. A hooded diamond pointed tool for dressing the face of a grinding wheel comprising a shank, a constricted pointed end portion, a tubular segment seated on said shank, a terminally upset pin piercing said shank and said tubular segment, and a U-shaped shield integral with said tubular segment having a longitudinally slotted trailing bight and leading leg portions.

5. A hooded diamond pointed tool for dressing the face of a grinding wheel comprising a shank having a circumferential groove, a constricted pointed end portion, a tubular segment having a plurality of indentations seated on said shank with said indentations seated in said groove, and a U-shaped shield integral with said tubular segment having a longitudinally slotted trailing bight and leading leg portions.

6. A hood for a diamond pointed dressing tool comprising a tubular member having two opposed axial slots opening at one end of said member and two partially circumferential slots communicating with the inner end of one of said axial slots, those segments of said tubular member intermediate said circumferential slots and

the terminal edge at which said axial slots open being straightened to form projecting wings.

7. In combination with a wheel dressing tool adapted to be cooled by a stream of coolant, a hood carried by the tool having a coolant-directing wall spaced outwardly from the tool and provided with a leading edge adapted to engage a wheel being dressed by the tool to form a chamber around the tool end, and said wall having coolant inlet and outlet passages sized for flow of coolant through the chamber while selectively retaining coolant around the tool end.

8. In combination with a wheel dressing tool having a shank portion and a diamond-carrying portion which is adapted to be cooled by a stream of coolant, a coolant confining and directing hood having a tubular portion mounted on the shank of said tool and a coolant confining wall depending from said tubular portion around the diamond-carrying portion of the tool in spaced relation therefrom to provide a chamber around said diamond-carrying portion, and said wall having coolant inlet and outlet passages therein sized for flow of coolant through the chamber while selectively retaining coolant around the 25 diamond-carrying portion of the tool.

9. In combination with a wheel dressing tool

having a diamond-carrying end portion adapted to be cooled by a stream of coolant, paired spaced shields disposed on opposite sides of the tool and extending in spaced relation from the diamond-carrying portion of the tool to provide a chamber around said portion, said shields having leading ends spaced farther apart than their trailing ends to provide inlet and outlet passageways to the chamber whereby coolant can flow through the chamber while being selectively retained therein to contact the diamond-carrying portion of the tool.

10. In a wheel dressing assembly including a dressing tool having a diamond-carrying end portion, a wheel adapted to be dressed by said tool, and means for flowing a stream of coolant adjacent the tool, the improvement which comprises a hood carried by the tool with a portion disposed around the diamond-carrying portion of the tool having a leading edge engaging the wheel to provide a chamber around said diamond-carrying portion of the tool receiving coolant from said stream to selectively retain the coolant in contact with said diamond-carrying portion for cooling the diamonds.

JOHN L. PETRIE.
